CLIFFORD H. OAKLEY, OF TRENTON, NEW JERSEY.

RUBBER-HEEL LIFT.

Application filed March 27, 1919. Serial No. 285,469.

To all whom it may concern:

Be it known that I, CLIFFORD H. OAKLEY, a citizen of the United States, and a resident of Trenton, in the county of Mercer and State of New Jersey, have invented an Improvement in Rubber-Heel Lifts, of which the following is a specification.

The present invention relates to an improvement in rubber heel lifts adapted to be attached to the heel of a shoe or the like, one object being to provide a readily attachable resilient lift which will embody the edge gripping qualities claimed for various lifts of the prior art together with structural features which render the improved lift more effectively edge gripping and more wear resisting than those heretofore in common use.

Among heels of the prior art are those of curved cross sectional contour having upper surfaces concave and bottom surfaces correspondingly convex. Ordinarily in applying a heel of this character, it has been found necessary to locate the fastening means relatively near the center and therefore correspondingly distant from the edges in order to secure sufficient deformation of the lift to make it conform to the flat heel surface of the shoe. In applying such a lift, it is necessary to deform the latter throughout its entire body, the center being displaced a relatively large distance with respect to the heel contacting edges, depending upon the degree of concavity of the lift. An examination of this structure from a practical mechanical point of view discloses that the resilient force residing in the material of a lift of the shape mentioned is tending constantly to force the center thereof downwardly and away from the heel. The strain in the material incident to operation of this force against the deforming force of the fastening means is especially effective at the portion through which the fastening means penetrate the lift and enter the heel. Thus, there results a constantly operating leverage action at the fastening portion with the edge portion acting as a fulcrum for the force applied at the position of the fastening means. Several disadvantages reside in a lift involving this particular construction. First, the constant strain acting through a relatively long lever tends to break down the resilient quality of the material of the lift at the point of fastening. Secondly, when the wearer of such a lift strikes it

against an upwardly or outwardly projecting object, such as the tread of a step, the long lever permits less resistance to the tearing of the lift away from the heel at the point of fastening, or in other words does not permit full utilization of the local resiliency of the material adjacent to the edge of the lift.

One of the important objects of applicant's invention is to provide a lift which may embody the advantage of close adherence to the heel without violent distortion of the entire body of the lift, and to insure such adherence by an allocation or positioning of the fastening means with respect to the edge of the lift and the deformed portion thereof. It is appreciated that there is not necessarily a novel idea merely in placing the fastening means more or less adjacent to the edge of the lift. However, in such forms of heel lifts as have heretofore been made, this placing of the fastening means has been of no special significance. Such placing becomes important only when it bears a definite functional relation to distorted portions of a heel lift having the novel conformations contemplated in applicant's structure.

One embodiment of my invention is illustrated in the drawings accompanying the present specification, in which,

Figure 1 is a top plan view of a preferred form of lift,

Figure 2, a transverse vertical section on the line 2-2 of Figure 1,

Figure 3, a vertical section on the line 3-3 of Figure 1,

Figure 4, a plan view of a modified form of lift,

Figure 5, a vertical section on the line 5-5 of Figure 4, and,

Figure 6, a transverse vertical section of the lift illustrated in Figure 1 applied to a heel.

The lift illustrated in the drawings may comprise a central core 1, shown clearly in Figures 2 and 3 as having parallel top and bottom surfaces and a deformable portion 2 surrounding said core and having a heel edge gripping rim 9, a concave upper surface between said rim and the core, and a correspondingly convex lower surface. A plurality of washers 3 may be imbedded in the material of the lift with their openings in register with recesses 4 adapted to receive nails 5 or other suitable means for securing

the lift to a heel, said recesses being positioned along the line of maximum distortion when the lift is so secured on a heel.

In the modification shown in Figure 4, a continuous recess or depression 8 in the core 1 separates the central portion of said core from a relatively narrow heel contacting portion 6, the continuity of which may be interrupted by transverse depressions thus permitting a free yielding of said portion 6 toward said transverse depressions and toward the continuous depression 8 when the lift is deformed by application to a heel in the manner contemplated.

15 The lift embodying my invention may be of substantially uniform thickness and the peripheral rim of the deformable portion is preferably normally in the same plane with or below the upper surface of the central core. An important feature of the invention is the positioning of the fastening means substantially in a line with the deepest portion of the concave upper surface, or along the line of maximum deformation or distortion. Thus, when the nails 5 are driven home, the portion 2 will be distorted along a line surrounding the undistorted portion or core 2 whereby the upper or concave surface will be displaced from its normal shape and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 30 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 35 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 40 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 45 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 50 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 55 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 60 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 65 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 70 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 75 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 80 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 85 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 90 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 95 and position into immediate contact with the heel surface, as illustrated in Figure 6, without displacement of the central core. Where the nails or other fastening means pass through the portion of the lift of greatest displacement, the displacement of material on each side of said fastening means or toward and away from the core will normally decrease by equal amounts in both directions, thus securing effective gripping 100 and position into immediate contact with the heel surface, as illustrated in Figure 6, without displacement of the central core.

Where the form illustrated in Figure 5 is used, it is contemplated that the grooves 7 and 8 will permit a yielding movement of the lift material in a direction toward the center as well as away from the center, thus more evenly distributing in both directions the strains set up when the fastening means are driven into the heel in such a manner as to distort the deformable portion of the lift.

From the foregoing description it will be seen that the improved construction provides a lift in which there is obtained in a 55 novel manner an effective gripping contact with the heel edge. The fastening means located and applied as described distribute the distorting forces evenly throughout the deformable portion of the lift and permits 60 effective edge gripping with a minimum of distortion. Thus, what might be referred to as local resilience of the material is permitted to effectively resist forces tending to disengage the lift from the heel, a result not 65 possible where the lift is attached to a heel at points relatively distant from the heel gripping edge.

I claim as my invention:—

1. A resilient heel lift comprising a central core having parallel flat top and bottom surfaces, the top surface being of a sufficient area to form a stable base to support the lift when resting thereon and a deformable portion of uniform width surrounding said core and having a top surface normally concave when undistorted with the outer edge in the plane of the flat top surface forming a peripheral heel engaging rim, and a convex bottom surface corresponding to the concave top surface, said deformable portion being arranged to be deformed upon attachment to a heel to bring portions of the concave top surface into contact with the bottom heel surface without displacement of the central core substantially as described.

2. A resilient heel lift having a central flat portion of a width equal to substantially one-third of the width of the lift and of substantial area lying in the plane of the edge of the lift and a surrounding deformable portion of substantially uniform width which surrounding portion presents a groove of substantially uniform width on the top 95 face of the lift and a corresponding ridge on the tread face and nail holes passing through the deformable portion along substantially the center thereof and extending at right angles to the plane of the lift.

In testimony whereof, I have signed my name to this specification this 22nd day of March 1919.

CLIFFORD H. OAKLEY.
